By Drake & Co. Atty's.

UNITED STATES PATENT OFFICE.

EDWARD P. BEACH, OF NEWARK, NEW JERSEY.

DESIGN FOR A FINGER-RING.

SPECIFICATION forming part of Design No. 20,736, dated May 19, 1891.

Application filed April 7, 1891. Serial No. 388,026. Term of patent 3½ years.

To all whom it may concern:

Be it known that I, EDWARD P. BEACH, a citizen of the United States, residing at Newark, in the county of Essex and State of New Jersey, have invented and produced a new and original Design for Finger-Rings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to said drawings, in which similar letters of reference indicate corresponding parts in each of the several figures whenever they occur, Figure 1 represents a plan, and Fig. 2 an elevation, of a finger-ring showing my design. Fig. 3 represents in plan a modification of the same.

The leading feature of my design consists

more particularly in the peculiar configuration of the seal portion of the ring, which presents the appearance of two strands or wires ²⁵ *a*, twisted and intertwined with one another and forming a single knot, the body of the ring having the appearance of a series of strands of wire *b*, lying laterally adjacent to one another and intersecting with said knot ³⁰ at each side, as clearly indicated in the drawings. In Fig. 3 is shown the same design double.

What I claim is—

The design for a finger-ring herein shown ³⁵ and described.

In testimony that I claim the foregoing I have hereunto set my hand this 3d day of April, 1891.

EDWARD P. BEACH.
